US0D1064977S

(12) **United States Design Patent** (10) **Patent No.:** **US D1,064,977 S**
(45) **Date of Patent:** **** Mar. 4, 2025**

(54) **FLOOR MAT SET**

(71) Applicant: **Shenzhen Yuanzhi Auto Accessories Co., Ltd**, Shenzhen (CN)

(72) Inventor: **Yue Yang**, Shenzhen (CN)

(73) Assignee: **Shenzhen Yuanzhi Auto Accessories Co., Ltd**, Shenzhen (CN)

(**) Term: **15 Years**

(21) Appl. No.: **29/872,055**

(22) Filed: **Mar. 6, 2023**

(30) **Foreign Application Priority Data**

Nov. 22, 2022 (CN) 202230781259.X

(51) **LOC (15) Cl.** **12-16**

(52) **U.S. Cl.** ..... **USPC D12/203**

(58) **Field of Classification Search**

USPC D12/203, 221; D6/582-586, 592-594

CPC B60R 13/01; B60N 3/044; B60N 3/04

(57) **CLAIM**

The ornamental design for a floor mat set, as shown and described.

DESCRIPTION

FIG. 1 is a front view of a floor mat set of its component one, showing my new design;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is a front perspective view thereof;

FIG. 8 is a front view of its component two;

FIG. 9 is a rear view thereof;

FIG. 10 is a top view thereof;

FIG. 11 is a bottom view thereof;

FIG. 12 is a left side view thereof;

FIG. 13 is a right side view thereof;

FIG. 14 is a front perspective view thereof;

FIG. 15 is a front view of its component three;

FIG. 16 is a rear view thereof;

FIG. 17 is a top view thereof;

FIG. 18 is a bottom view thereof;

FIG. 19 is a left side view thereof;

FIG. 20 is a right side view thereof;

FIG. 21 is a front perspective view thereof;

FIG. 22 is a front view thereof of the combination state; and,

FIG. 23 is a front perspective view thereof of the combination state.
